ROTARY SPARK GAP

Russell S. Stanton, Waban, Mass., assignor, by
mesne assignments, to the United States of
America as represented by the Secretary of the
Navy

Application October 9, 1945, Serial No. 621,338

11 Claims. (Cl. 313—149)

1 This invention relates to a rotary spark gap generator and more particularly to such a generator adapted to provide uniform spark generation and long electrode life under conditions of a high current flow across the spark gap.

Rotary spark gap generators heretofore known in the art and used as modulator switches for throwing an electrical pulse upon a magnetron are usually so designed that the faces of the sparking electrodes are parallel at the instant sparking occurs. Such generators have proven to be impractical for the handling of large currents of the order of one thousand amperes at usual duty cycles, since such currents rapidly wear electrode surfaces to conformations which cause time and amplitude jitter, thereby requiring frequent electrode changes. This invention provides a rotary spark gap generator in which the electrodes have a novel conformation which reduces to a minimum the jitter common to spark gap generators as heretofore designed and which, in addition, provides a spark gap generator in which the electrodes are so designed as to insure long life and uniform wear thereof.

An object of this invention is to provide a novel rotary spark gap generator for high current use in which the electrodes are so designed as to provide a minimum of jitter of pulse time and amplitude of the sparks generated thereby.

Another object of this invention is to provide a rotary spark gap generator in which the electrodes are oriented in a novel manner with respect to each other so as to insure long life and uniform wear thereof.

A further object of this invention is to provide a rotary spark gap generator in which the spark generated will originate from the same electrode each time it is generated.

A particular object of this invention is to provide a rotary spark gap generator in which the faces of the electrode are at an angle with respect to each other at the instant sparking occurs.

A more particular object of this invention is to provide a rotary spark gap generator in which one of the electrodes presents a surface of small radius of curvature as compared to the radius of the opposite electrode at the instant sparking occurs.

Further objects and advantages of this invention, as well as its construction, arrangement, and operation, will be apparent from the following description and claims in connection with the accompanying drawings, in which:

Fig. 1 is a front view of a schematic diagram **2** of a spark gap generator illustrating the relative orientation of a pair of electrodes as contemplated by my invention;

Fig. 2 is a side view of spark gap generator shown in Fig. 1 further illustrating the relative orientation of the electrodes of the generator;

Fig. 3 is a schematic diagram of the spark gap generator illustrating the manner of wear of the electrodes as shown in Fig. 1;

Fig. 4 is a schematic diagram of the spark gap generator illustrating the manner of wear of the electrodes as shown in Fig. 2.

Referring to Figs. 1 and 2 there is shown a pair of electrodes 20 and 21 of a spark gap generator as contemplated by my invention. Electrode 20 is a stationary or positive electrode, while electrode 21 which is a negative electrode is a rotary electrode, being radially mounted upon a circular disc 22.

While a pair of electrodes are illustrated, the complete spark gap generator may consist of a single stationary electrode and a plurality of radially mounted rotary electrodes, a single rotary electrode and a series of radially mounted stationary electrodes, or a plurality of stationary electrodes and a plurality of radially mounted rotary electrodes. A design used in existing equipment consists of a single stationary electrode and six rotary electrodes placed radially upon disc 22, which in turn rotates about a shaft (not shown) as an axis.

As heretofore stated, rotary spark gap generators of common design have proven unsatisfactory for handling large currents of the order of one thousand amperes due to the high rate of wear of the electrodes and because of the considerable jitter of pulse time and amplitude of the sparks developed by such generators. It has been discovered that this unsteady operation occurs when the spark discharge does not originate from the same electrode each time the spark is generated.

In order to control the spark discharge and cause it to originate from the same electrode each time, the stationary or positive electrode 20 is provided with a surface having a short radius of curvature to ionize the air in its vicinity, while the rotary or negative electrode 21 is provided with a surface of longer radius of curvature in order to produce less ionization of the air in the vicinity of the rotary electrode. As shown in

Fig. 1 this is accomplished by, in effect, pointing the end electrode 20 towards the approaching electrode 21 travelling in its rotary path. As illustrated in Figs. 1 and 2, rotary electrode 21, or a plurality of rotary electrodes if such be used,

Fig. 1 is a front view of a schematic diagram

is placed on a rotary disc 22. In the plane of this disc fixed electrode 20 is parallel to rotary electrode 21, but at the instant electrodes 20 and 21 are disposed sufficiently close to each other for a spark discharge to occur across them, fixed electrode 20 forms an angle, preferably approximately 30 degrees, with the radial line of rotary electrode 21 in a plane drawn through this radius at right angles to the disc. In other words the fixed electrode is placed parallel to the rotary electrode, or electrodes, in the plane of the disc but approximately at an angle of 30 degrees with a plane perpendicular to the plane of the disc passing through the rotary electrode. As a result of this structure, fixed electrode 20 presents a surface of small radius as compared to the cylindrical surface of revolving electrode 21. As the electrode wear progresses, an ellipse of short radii of curvature is continually presented, and as fixed electrode 20 becomes shorter, it makes its spark contact lower down on the surface of each rotary electrode. The relative rate of deformation of the electrodes is illustrated in Figs. 3 and 4. The relative rate of wear of the fixed and rotary electrodes is chosen (by electrode size, polarity, and number of rotary electrodes) so that when the fixed electrode is completely worn away only a small part of the total material of the rotary electrodes is consumed. By reference to Figs. 3 and 4, it will readily be understood that as the electrode wear progresses, an ellipse having certain short radii of curvature is continually presented, thereby providing fixed electrode with a short radius of curvature in order to ionize the air in its vicinity. At the same time, rotary electrode 21 (negative electrode) suffers very little deformation and therefore presents no surfaces having short radii of curvature. In this manner, the spark discharge is caused to be initiated from the same electrode each time it is generated, throughout the usable life of the electrodes.

While a particular arrangement of my invention has been disclosed and described it is to be understood that various modifications and changes may be made without departing from the spirit and scope thereof as set forth in the appended claims.

What is claimed is:

1. A rotary spark gap generator comprising a rotary electrode mounted upon a rotatable disc, the longitudinal axis of said rotary electrode being disposed in the plane of said disc, and a stationary electrode, said stationary electrode being oriented parallel to the plane of said disc and at an angle to the plane perpendicular to the plane of said disc passing through the longitudinal axis of said rotary electrode.

2. A rotary spark gap generator comprising a plurality of rotary electrodes radially mounted upon a rotatable disc, the longitudinal axis of each of said rotary electrodes being disposed in the plane of said disc, and a stationary electrode, said stationary electrode being oriented parallel to the plane of said disc and oriented at an angle to the plane perpendicular to the plane of said disc passing through the rotary electrode adjacent said stationary electrode at the instant a spark discharge is generated between said electrodes.

3. A rotary spark gap generator comprising a plurality of rotary electrodes radially mounted upon a rotatable disc, the longitudinal axis of each of said rotary electrodes being disposed in the plane of said disc, and a stationary electrode, said stationary electrode being oriented parallel

to the plane of said disc and oriented at an angle to the plane perpendicular to the plane of said disc passing through the longitudinal axis of the rotary electrode adjacent said fixed electrode at the instant a spark discharge is generated across said electrodes, said fixed electrode having a relatively short radius of curvature as compared to the radius of curvature of each of said rotary electrodes.

10 4. A rotary spark gap generator comprising a stationary electrode and an electrode rotatable in a fixed plane, said stationary electrode being oriented parallel to the plane of rotation of said rotary electrode, said stationary electrode also

15 being oriented at an acute angle to said rotary electrode at the instant a spark discharge is generated between said electrodes.

5. A rotary spark gap generator comprising a rotary electrode adapted to generate a surface of

20 revolution upon the rotation thereof, and a stationary electrode disposed in a spaced relationship to said surface of revolution, the distance between said stationary electrode and said surface of revolution being constant throughout the

25 length of said stationary electrode, said stationary electrode being disposed at an acute angle with respect to said rotary electrode at the instant a spark discharge is generated between said electrodes, said rotary electrode and said stationary electrode making different angles with respect to the direction of rotation of said rotary electrode at said instant of spark discharge.

6. A rotary spark gap generator comprising a stationary electrode and a rotary electrode adapt-

35 ed to rotate within a fixed plane of rotation, a substantial portion of said stationary electrode being oriented parallel to said plane of rotation, the free end of said substantial portion being dis-

30 posed in close proximity to said rotary electrode at the instant of a spark gap discharge, said stationary electrode being oriented relative to said

35 plane of rotation so that at an instant of a spark gap discharge between said electrodes, said stationary electrode intersects said rotary electrode

40 at an acute angle, whereby the spacing between said electrodes at the instant of a spark gap dis-

45 charge remains constant independent of the wear of said rotary electrode and of the substantial portion of said stationary electrode.

7. In a spark gap generator, a stationary elec-

50 trode and an electrode rotatable in a fixed plane, said stationary electrode being oriented parallel to the plane of rotation of said rotatable elec-

55 trode, said stationary electrode and said rotatable electrode making different angles with respect to the direction of rotation of said rotatable elec-

60 trode at the instant of a spark discharge between said electrodes.

8. In a spark gap generator, an elongated sta-

65 tionary electrode and at least one elongated elec-

trode adapted to rotate with its longitudinal axis radial to the axis of rotation, means supporting

70 said stationary electrode with its axis parallel to and displaced from the plane of rotation of said

75 rotatable electrode, said stationary electrode be-

ing oriented with respect to said axis of rotation such that said rotatable electrode is adapted to

pass over the length of said stationary electrode once each revolution of said rotatable electrode,

75 said rotatable electrode when rotated in the de-

sired direction making an acute angle with re-

9. In a spark gap generator, an elongated sta-

tionary cylindrical electrode and at least one elongated cylindrical electrode adapted to rotate with its longitudinal axis radial to the axis of rotation, means supporting said stationary electrode with its longitudinal axis parallel to the plane of rotation of said rotatable electrode, said stationary electrode being disposed with respect to the said axis of rotation such that said rotatable electrode passes over the length of said stationary electrode once for each revolution and makes an acute angle with said stationary electrode which increases in magnitude as it passes over one end of said stationary electrode to the other end of said stationary electrode.

10. In a spark gap generator, a movable electrode defining during movement thereof a predetermined surface, a stationary electrode, and means supporting said stationary electrode in spaced relationship to said surface whereby the distance between said stationary electrode and 20 said surface is maintained constant during movement of said movable electrode past said stationary electrode, said distance being of a magnitude to permit a spark discharge between said electrodes upon the application of a predetermined potential thereto, said stationary electrode further being oriented at an acute angle with respect to said movable electrode during movement of said movable electrode past said stationary electrode, said electrodes defining different angles 30 with respect to the direction of motion of said movable electrode throughout the movement of said movable electrode past said stationary electrode.

- 5 11. In a spark gap generator, a movable, elongated, cylindrical electrode, arranged to rotate in a plane and extending radially from the axis of rotation, an elongated, stationary electrode of cylindrical shape supported with its axis parallel to the plane of rotation of said movable electrode and spaced from said plane of rotation an amount to permit a spark discharge between said movable and stationary electrodes as said movable electrode is rotated past said stationary electrode, said stationary electrode further being oriented at an acute angle with respect to said movable electrode during rotation of said movable electrode in the desired direction past said stationary electrode, which angle increases in magnitude as said movable electrode passes by said stationary electrode.
